UNITED STATES PATENT OFFICE.

ARTHUR W. WALKER, OF MALDEN, MASSACHUSETTS.

DESIGN FOR A STOVE.

No. 38,934.

Specification for Design.

Patented Dec. 3, 1907.

Application filed September 11, 1907. Serial No. 392,409. Term of patent 14 years.

To all whom it may concern:

Be it known that I, ARTHUR W. WALKER, a citizen of the United States, residing at Malden, in the county of Middlesex and State of Massachusetts, have invented a new, original, and ornamental Design for Stoves, of which the following is a specification, reference being had to the accompanying drawing, forming part thereof.

The figure is a perspective view of a stove, showing my new design.

I claim:

The ornamental design for a stove, as shown.

ARTHUR W. WALKER.
